DESIGN FOR A COSMETIC DISPLAY STAND

Claire Dorfman, Brooklyn, N. Y.

Application April 8, 1939, Serial No. 84,162

Term of patent 3½ years

To all whom it may concern:

Be it known that I, Claire Dorfman, a citizen of the United States and a resident of the city of New York, in the county of Kings, Borough of Brooklyn, and State of New York, have invented a new, original, and ornamental Design for a Cosmetic Display Stand, of which the following is a specification, reference being had to the accompanying drawing, forming part thereof.

The figure is a perspective view of a cosmetic display stand embodying my new design.

I claim:

The ornamental design for a cosmetic display stand, substantially as shown.

CLAIRES DORFMAN.
